UNITED STATES PATENT OFFICE.

FRANK O. WILLEY, DECEASED, LATE OF INDIANAPOLIS, INDIANA, BY ROLLA E. WILLEY, ADMINISTRATOR, OF INDIANAPOLIS, INDIANA.

COMBINATION PADLOCK.

Application filed April 28, 1927. Serial No. 187,245.

The invention relates to a combination padlock and has for its general object to provide a lock of the indicated type improved in various particulars with a view 5 to effect a secure locking of the same, to prevent or to make difficult the opening of the lock by unauthorized parties, as well as to provide for changing the combination when desired, with facility.

10 A further important object of the invention is to provide a lock of the indicated character so formed and arranged as to facilitate the assembling and disassembling of the parts.

15 The nature of the invention and its distinguishing features and advantages will clearly appear as the description proceeds.

Reference is to be had to the accompanying drawings forming a part of this specification, it being understood that the drawings 20 are merely illustrative of one form of the invention.

Figure 1 is an elevation of a combination padlock embodying the invention.

25 Figure 2 is a section on the plane indicated by the line 3—3 of Figure 4, showing the locking shackle and the bolt carried thereby in the locking position.

Figure 3 is a view similar to Figure 2, but 30 showing the shackle in the unlocking position.

Figure 4 is a section on the line 4—4 of Figure 3.

Figure 5 is a section mainly taken on the 35 line 5—5 of Figure 4, but with the disks and washers in central section.

Figure 6 is a perspective view of one of the hub sections.

Figure 7 is a perspective view of the 40 second hub section.

Figure 8 is an elevation of the shackle and bolt.

Figure 9 is a face view of one of the permutation disks.

45 Figure 10 is a section on the line 10—10 of Figure 9.

Figure 11 is a front elevation of the housing.

Figure 12 is a rear view of the housing 50 portion shown in Figure 11.

Figure 13 is an elevation of one of the washers.

Figure 14 is a face view of another of the 55 permutation disks, the view being similar to Figure 9 which shows the intermediate disk.

In carrying out the invention in practice in accordance with the illustrated example, a housing 15 is provided divided in the medial plane to provide a front housing section 23 and a rear housing section 123. 60 The front housing section has a zero mark or indicator 16 thereon near the periphery and is provided interiorly with a trip lug 17. See Figures 4, 11 and 12. A shackle 18 is provided with a locking bolt 19 to move in 65 unison with the movements of the shackle. Said bolt 19 is swiveled by a sleeve 20 to the inner end of the shank of the shackle 18 and has a lateral bolt or locking flange 21 formed with a broad tongue 22. A front 70 hub section 24 is provided and formed with a flange 25 and a mating hub section 26 extends through the rear housing section 123 and provided with a flange 27. The hub section 24 has a transverse slot 28 which is 75 adapted to receive a corresponding projection 29 on the hub section 26. The front hub section 24 is formed with a vertical slot 30, and a registering slot 31 is formed in the projection 29, said slots 30 and 31 being 80 adapted to accommodate the bolt flange 21 and its tongue 22.

In the sides of the hub section 24 are grooves 32 and registering grooves 33 are formed in the sides of projection 29. Said 85 grooves 32, 33 are adapted to receive fork members 34 on the plate 35, which is provided for the purpose of holding the hub sections in assembled position and preventing displacement thereof, and preventing the 90 dismembering of the lock. The plate 35 is tightly but removably held in the flange of the rear casing section 123, as indicated at 36 in Figures 2 and 3.

I have shown three permutation disks 95 bearing the designations respectively 37, 38, 39, the innermost disk being numbered 37, the intermediate disk 38 and the outermost disk being numbered 39. The lug 17 is positioned between two adjacent teeth of disk 37 in the plane of said disk. Said innermost disk 37 has one offset tooth 40, disposed toward the adjacent intermediate disk 38. Said innermost disk and the outermost disk 100 39 have slots 43 to receive the tongue 22 of disk 37 in one position of the bolt. Also the disk 37 has blind recesses 44 at the eye or bore thereof, which the tongue 22 will enter in an unauthorized attempt to open the lock. The numeral 45 indicates a slot in the inter- 105 110

mediate disk 38 to be brought into register with the slots 43 when the bolt 19 is in the operation of locking the lock. The intermediate disk 38 has teeth 41, 42, offset oppositely from the general plane of said disk, the one tooth being adapted to be engaged by the offset tooth 40 on disk 37 and the other tooth 42 being adapted to engage the one offset lug at the inner side of the outermost disk 39.

In front of the front housing section 23 is a dial 50 held by the flange 25 of the front hub section 24. A ball 46 loosely set in the dial 50 is adapted to successively engage in any of the annular series of depressions 47 in the housing section 23. A second ball 48 is adapted to engage in a single depression 49 in the housing section 23.

In the operation of bringing the slots 43, 45, of the respective permutation disks in register for opening the lock, the following occurs. The front housing section 23 is turned and the turning, owing to the engagement of the lug 17 between two adjacent

teeth, turns the disk 37 which by engagement of its tooth 40 with a tooth 41 or 42, causes said disk 38 to be also turned, and since the outermost disk 39 is similar to 37 as regards offset tooth corresponding with

the tooth 40, the other offset tooth of disk 38 will cause said disk 39 to turn. In aligning the slots 43 of the innermost disk 37 and outermost disk 39 with the slot 45 of the intermediate disk, and the intermediate disk

having picked up and caused to turn the front disk 39, the three disks turn with the housing section 23 until the slot 43 in the innermost disk is in register with the slots 30, 31 of the hub section. The housing section 23 is then turned counter-clockwise one turn, in order to pick up the intermediate disk 38. After the slot 45 of the intermediate disk has been aligned with the slots 30, 31, it is necessary to turn clockwise and align the first or outermost disk 39 so that

the slots 43, 45 of all three disks are in register. In aligning the disks as described by touch to register the various slots 43, 45 with the slots 30, 31 of the hub sections, the touch or feel of the operator on the ball 46 will determine the number of graduations of the dial over which the ball 46 is caused to travel in a given partial turn of housing section 23, the operator being enabled to determine by

feel the engagement of the ball 46 with the successive depressions 47. The start of the movement in turning the dial 50 is with the ball 46 in radial alignment with the zero mark or projection 16.

In changing the combination, the shackle is moved outwardly to bring the tongue 22 of bolt 19 in the outer position shown in Figure 4 and extending into the slots 43. At this time the shackle and its bolt 19 are in the unlocked position. Then the plate

35 is displaced to disengage its fork members 24 from the side recess 32, 33. The hub sections may now be separated axially, exposing the inner permutation disk 37. A limited number of changes in the combination may be made by changing the point of engagement between the lug 17 and the teeth of disk 37. A great number of changes in the combination may be made by removing the disks 38, 39, and varying the particular teeth that are bent out of the general plane to be engaged by the lug 40. That is to say, the offset tooth 40 may be variously selected for offsetting, and the offset teeth 41 may be varied as to their position so that the said offset teeth 41, 42, bear a particular relation to the slot 45, or the tooth 40 may be caused to bear a given relation to the slot 43.

When the ball 48 is at the single depression 49 in the housing section 23 the ball 46 will be adjacent the zero mark 16.

In the plate 35 is a slot 51 (see Figures 2, 3 and 4) which is in register with the central slots 30, 31 in the hub sections 24, 26, to permit the entrance of the flange 21 of bolt 19 and the tongue 22 in the operation of opening the lock.

The numeral 52 indicates washers disposed between the permutation disks 37, 38, 39, said washers having slots 53 adapted to register with the slots of the permutation disks when the lock is opened. On each washer 52 at the interior is a lug 54 adapted to enter the vertical slot 30 in the hub section 24, as shown in Figure 4, to prevent turning of the washers.

I would state furthermore that while the illustrated example constitutes a practical embodiment of the invention, I do not limit myself strictly to the exact details herein illustrated, since, manifestly, the same can be considerably varied without departure from the spirit of the invention as defined in the appended claims.

I claim:

1. A combination padlock including a housing, a shackle held to said housing and movable relatively thereto to a locking or unlocking position, a slidable plate formed with fork members and a slot, a bolt on the shackle adapted to be projected into said slot, a series of permutation disks within the housing, a hub formed of sections about which said disks may turn separately, said hub sections presenting registering slots in line with the slot in said plate and formed with side slots to receive said fork members, said disks having each a slot adapted to be registered with the slot of the plate and with the slots in the hub, and a lateral member on said bolt adapted to be accommodated in the slots of the disks and plate or to be moved into the said registering slots of the hub sections.

2. A combination padlock including a

housing, a shackle held to said housing and movable relatively thereto to a locking or unlocking position, a slideable plate formed with a slot and fork members, a bolt on the shackle adapted to be projected into said slot, a series of permutation disks within the housing, a hub formed of sections about which said disks may turn separately, and to be brought into register, a shackle extending into said housing, a bolt on the shackle in the plane thereof and a member on said bolt projecting laterally and adapted to be accommodated in one position of the shackle in the slot of the hub and receivable in another position of the bolt in the slots of the disks. 70

10 slots in line with the slot in said plate, said disks having each a slot adapted to be registered with the slot of the plate and with the slots in the hub, and a lateral member on said bolt; together with washers between the permutation disks, said washers having projections projecting into the slot in one of the hub sections.

in one of the hub sections.

3. A combination padlock including a housing, a shackle held to said housing and movable relatively thereto to a locking or unlocking position, a slideable plate formed with a slot and fork members, a bolt on the shackle adapted to be projected into said slot, a series of permutation disks within the housing, a hub formed of sections separable by an axial movement about which hub sections said disks may turn separately, said hub sections presenting registering slots in line with the slot in said plate and with side slots accommodating said fork members, said disks having each a slot adapted to be registered with the slot of the plate and with the slots in the hub, and a lateral member on said bolt adapted to be accommodated in the slots of the disks and plate or to be moved into the said registering slots of the hub sections.

4. A combination padlock including a housing, a shackle held to said housing and movable relatively thereto to a locking or unlocking position, a slidable plate formed with a slot, a bolt on the shackle adapted to be projected into said slot, a series of permutation disks within the housing, a hub formed of sections about which said disks may turn separately, said hub sections presenting registering slots in line with the slot in said plate, said disks having each a slot adapted to be registered with the slot of the plate and with the slots in the hub, and a lateral member on said bolt; together with a graduated dial, a ball incorporated in said dial and projecting through the same at the back and front and a second ball in said dial, the said housing having an annular series of depressions adapted to be engaged by the first mentioned ball, and a single depression adapted to be engaged by the second mentioned ball.

60 5. A combination padlock including a housing element, a hub about which said housing element may turn, a series of permutation disks within the housing and formed with slots, said hub presenting a slot
65 with which the slots of the disks are adapt-

6. A combination padlock including a casing having a turnable part, a shackle movable relatively to the casing to locking and unlocking position, a bolt on said shackle and constrained to move therewith in the movements of the shackle to locked and unlocked positions, a hub formed in two sections separable axially, means to hold said hub sections against separation, and locking means operable by said turnable part, said bolt being movable with the shackle into and out of engagement with said locking means as the shackle moves to and from its said positions.

7. A combination padlock including a casing having a turnable part, a shackle movable relatively to the casing to locking and unlocking position, a bolt on said shackle and movable therewith, a hub formed in two sections separable axially, said hub sections having grooves, and a plate engageable with both hub sections at said grooves to hold the hub sections against separation, said hub sections having registering slots in which a member of the bolt is movable.

8. A combination padlock, including a housing element, a hub about which said housing element may turn, a series of permutation disks within the housing, said disks having teeth and formed with slots, said hub presenting a slot with which the slots of the disks are adapted to be brought into register, a lug on said housing disposed between adjacent teeth of one of said disks, and means to cause the turning of said disk to cause turning of the remaining disks. 100 105 110

9. A combination padlock, including a housing element, a hub about which said housing element may turn, a series of permutation disks within the housing, said disks having teeth and formed with slots, said hub presenting a slot with which the slots of the disks are adapted to be brought into register, a lug on said housing disposed between adjacent teeth of one of said disks, means to cause the turning of said disk to cause turning of the remaining disks, a shackle extending into said housing, a bolt on the shackle in the plane thereof, and a member on said bolt projecting laterally and adapted to be accommodated in one position of the shackle in the slot of the hub and extending in another position of the bolt into the slots of the disk. 110 115 120 125

10. In a combination padlock, a turnable element bearing a zero mark, a member at the back of said turnable element having an 139

- annular series of depressions, and an element carried by said turnable element and engageable in said depressions, said member at the back having a single depression additional to the series of depressions, an element carried by said turnable element and engageable in said single depression when the said first carried element is adjacent said zero mark, a bolt, means to move said bolt, and 10 means to maintain said bolt in the locking position, said means subject to the turning of said first mentioned element.

11. In a combination padlock, a series of permutation disks having peripheral bendable teeth, one of the teeth of certain of said disks being offset laterally from the general plane of the disk for causing one disk to give turning movement to another disk, the remainder of said teeth on the disks being in the general plane of the disks. 15
